Patented Oct. 30, 1973

228,882

PROTECTOR FOR LOAVES OF BREAD

Robert M. Bish, 2112 Hackney, Houston, Tex. 77023, and Jewell W. Davis, Box 361-X, Rte. 2, Pearland, Tex. 77581

Filed June 7, 1971, Ser. No. 150,896

Term of patent 14 years

Int. Cl. D9—99

U.S. Cl. D9—184

FIG. 1 is a top front perspective view of a protector for loaves of bread showing our new design;

FIG. 2 is a bottom rear perspective view thereof;

FIG. 3 is an end elevational view thereof.

We claim:

The ornamental design for a protector for loaves of bread, as shown.
